(74) Attorney, Agent, or Firm—Foley & Lardner

(57) **CLAIM**

The ornamental design for a playard, as shown and described.

DESCRIPTION

FIG. 1 is a perspective view showing the playard of our new design;

FIG. 2 is a top plan view thereof;

FIG. 3 is a bottom plan view thereof;

FIG. 4 is a left side elevation view thereof, the right side elevation being a mirror image of the left side elevation view;

FIG. 5 is a front elevation view thereof, the rear elevation view being a mirror image of the front elevation view; FIG. 6 is a partial cross section thereof, taken along line 6—6 in FIG. 4, to more clearly show the inside thereof; and, FIG. 7 is a partial cross section thereof, taken along line

FIG. 7 is a partial cross section thereof, taken along line 7-7 in FIG. 5, to more clearly show the inside thereof. The broken lines are for illustrative purposes only and do not form part of the claimed design.
